(57) **CLAIM**

The ornamental design for a vanity, as shown and described.

DESCRIPTION

FIG. 1 is a front right perspective view of a first preferred embodiment of a vanity in accordance with our new design;

FIG. 2 is a front elevation view of the vanity shown in FIG. 1;

FIG. 3 is a rear elevation view of the vanity shown in FIG. 1;

FIG. 4 is a top plan view of the vanity shown in FIG. 1;

FIG. 5 is a bottom plan view of the vanity shown in FIG. 1;

FIG. 6 is a right side elevation view of the vanity shown in FIG. 1, with the left side being a mirror image;

FIG. 7 is a front right perspective view of a second preferred embodiment of a vanity with a filler strip in accordance with our new design;

FIG. 8 is front elevation view of the vanity shown in FIG. 7;

FIG. 9 is a rear elevation view of the vanity shown in FIG. 7;

FIG. 10 is a top plan view of the vanity shown in FIG. 7;

FIG. 11 is a bottom plan view of the vanity shown in FIG. 7;

FIG. 12 is a front left perspective view of a third preferred embodiment of a vanity with a filler strip in accordance with our new design, with the right side elevation view being identical to FIG. 6;

FIG. 13 is front elevation view of the vanity shown in FIG. 12;

FIG. 14 is a rear elevation view of the vanity shown in FIG. 13; and,

FIG. 15 is a left side elevation view of the vanity shown in FIG. 13.
